UNITED STATES PATENT OFFICE.

PAUL LOUIS TOUSSAINT HÉROULT, OF NEW YORK, N. Y., ASSIGNOR TO ELECTRODE COMPANY OF AMERICA, OF NIAGARA FALLS, NEW YORK, A CORPORATION OF NEW YORK.

APPARATUS FOR GRAPHITIZING CARBON.

1,084,274.

Specification of Letters Patent.

Patented Jan. 13, 1914.

Application filed February 16, 1912. Serial No. 678,128.

To all whom it may concern:

Be it known that I, PAUL LOUIS TOUSSAINT HÉROULT, a citizen of the Republic of France, residing in the borough of Manhattan, city, county, and State of New York, have invented certain new and useful Improvements in Apparatus for Graphitizing Carbon, of which the following is a specification.

10 This invention aims to provide a comparatively quick and economical means of graphitizing carbon for the manufacture of large electrodes for electric furnaces, and for various other uses, especially in the electrical field where graphitized carbon is desirable. For this purpose the carbon, broken to a suitable size, is first subjected to a blast of air under such conditions that it is considerably heated, and is then heated to a 15 graphitizing temperature electrically. The preheating of the carbon facilitates its conversion into graphite under the electrical heat, and economizes the consumption of electricity involved in the second stage of 20 the process. The process is also advantageous in that it permits of a ready regulation of the quantity subjected to the electrical current at a given time, and permits also of a very nice regulation of the rate of treatment.

25 The accompanying drawing illustrates partly in vertical section and partly in side elevation an apparatus and process embodying the invention.

30 Referring now to the embodiment of the invention illustrated, the apparatus comprises a comparatively short shaft A of brick-work or the like forming the discharge end of the furnace, above which is a 35 similarly constructed shaft B, flaring at its lower end so as to facilitate the discharge of the product, and constituting the electrical furnace proper. At opposite ends of the electric furnace B are two heavy carbon 40 electrodes C and D, connected respectively to the plus and minus ends of the electric circuit. The broken carbon descends at a 45 determined rate through the furnace B and forms a resistance between the electrodes C and D, so that it is heated by the current to a 50 degree sufficient to thoroughly graphitize it. The amount of resistance offered by the body of carbon in the furnace B may be readily increased or diminished by adding

or removing horizontal rings of brick-work 55 in the furnace wall.

Above the electrical furnace is a shaft E, open at the top for the escape of air and gases, the interior of this shaft having a diameter at least as small as that of the upper end of the electric furnace B so as to 60 freely discharge the carbon thereinto, the shaft E forming preferably a direct continuation of the electric furnace. In the lower part of the shaft E is a ring F extending 65 around the wall, with ports G opening inward, the ring being connected by a pipe H with a source of air under pressure.

The graphitizing material is discharged through the base A of the furnace on to a 70 traveling carrier, such for example as the table J, the shaft K of which is mounted in bearings L and is rotated slowly by an electric motor M the speed of which is adjustable by means of a rheostat N. The top of 75 the table is slightly below the bottom of the base A of the furnace, so that as the table is rotated it carries a part of the finished product with it, until the latter arrives at an oblique scraper O which is fixed in position 80 and bears on the top of the table so as to scrape off the product into suitable bins.

The furnace being once in operation, the passage of the electric current graphitizes the carbon in the furnace B. The air forced 85 in to the preheating shaft through the tube F, combines with the carbon and hydrocarbons. In other words it generates a large quantity of heat which preheats the carbon above. A continuous supply from the crushers is passed into the top of the shaft, through a chute P for example, space being 90 provided around this chute for the escape of air and gases. The carbon is broken to small size, such for example as that known as nut 95 size, before being fed to the chute. If the graphitization is not sufficiently thorough, the speed of rotation of the table J is reduced, and with it the rate of passage of the carbon through the furnace; in the contrary 100 case the speed of rotation of the table is increased. The variation of the rate of passage of the carbon through the furnace varies both the preheating effect and the 105 effect of the subjection to the electric current. The relation between the preheating and the electrical treatment can be varied independently of the rate of passage of the

carbon, by varying the quantity of air forced into the pipe H; or by varying the current transmitted through the electrodes C and D. After the product has been scraped off the table, it may be crushed and mixed with suitable binders, and molded or pressed into the desired articles.

What I claim is:—

1. An apparatus for graphitizing carbon comprising a tubular graphitizing chamber, and a tubular heating chamber forming a direct extension of the graphitizing chamber, the lower end of the heating chamber coinciding in size with and constituting the upper end of the graphitizing chamber so that the material passes at substantially the same rate through the lower end of the heating chamber and the upper portion of the graphitizing chamber and so that the gases from the graphitizing chamber pass through the body of the material into the heating chamber.
2. An apparatus for graphitizing carbon comprising a tubular graphitizing chamber, and a tubular heating chamber forming a direct extension of the graphitizing chamber, the lower end of the heating chamber coinciding in size with and constituting the upper end of the graphitizing chamber so that the material passes at substantially the same rate through the lower end of the heating chamber and the upper portion of the

graphitizing chamber and so that the gases from the graphitizing chamber pass through the body of the material into the heating chamber and means for introducing air into the body of the material in the bottom of the heating chamber to combine with said gases and preheat the material.

3. An apparatus for graphitizing carbon comprising a vertical tubular graphitizing chamber with an electrode at each end for passing a current of electricity through the carbon, said chamber being flared at the lower end to permit the free passage of the product.

4. An apparatus for graphitizing carbon comprising a vertical, tubular, graphitizing chamber with an electrode at each end for passing a current of electricity through the carbon, said chamber being built of horizontal rings of brickwork and adapted to be readily increased or diminished in length by adding or removing rings of such brickwork, and means for causing the passage of the carbon through said chamber continuously and at a regulable rate.

In witness whereof, I have hereunto signed my name in the presence of two subscribing witnesses.

PAUL LOUIS TOUSSAINT HÉROULT.
